Walter S. Jones

UNITED STATES PATENT OFFICE

2,021,730

CLIP MEMBER

Walter I. Jones, Arlington, Mass., assignor to
 United-Carr Fastener Corporation, Cambridge,
 Mass., a corporation of Massachusetts

Application July 14, 1934, Serial No. 735,221

4 Claims. (Cl. 24—85)

My invention relates to a wire-holding clip with pin means for attaching it to fabrics and fabric-covered articles.

In the drawing, which illustrates an embodiment of my invention:—

Fig. 1 is a front view of one form of my invention;

Fig. 2 is a section taken on the line 2—2 of Fig. 1;

Fig. 3 is a rear view of the form shown in Fig. 1;

Fig. 4 is a section taken on the line 4—4 of Fig. 1; and

Fig. 5 is a front view of a form of my invention showing a section of wire in position.

The specific form of my invention as shown in the drawing presents a simple and sturdy wire-clip, easily attachable to fabric.

The wire-clip 1 is formed from the cap itself

20 for purposes of economy, simplicity and strength. It has a slight reverse curve as shown in Fig. 2 at 1a, for the purpose of clipping the wire firmly against the face of the cap with a spring action. The cap 2 is slightly dome-shaped for 25 strength and appearance and is secured to the circular head of the pin 3 by a flange 4 which is bent over the pin 3. To prevent rotation of the cap on the head, I have provided the flange with two extensions 5—5 adapted to bend inwardly on 30 either side of the pin, thus holding the cap in proper position relative to the pin (Fig. 3).

Where the pin used is a single one, as in Fig. 3, it is necessary to provide means to keep the pin upright in the fabric, lest the wire-clip 1 be 35 turned upside down. To this end, I have provided the flange with another pair of extensions, in the form of sharpened prongs 6—6, bent outwardly toward the pin 3 (Figs. 2 and 3) and adjacent to it. These prongs allow the fabric 40 to pass readily between themselves and the pin, but their sharp points hold the fabric and prevent the pin from turning.

Since the fabric must be allowed to pass between the cap and the pin means to effect complete engagement, I have bent the pin 3 away from its circular head 7 at the point 8 where the head 7 begins. I have further bent the pin in the opposite direction at a point 9 near the top of the cap 2. These two bends remove the circular head from the pin and leave a space for the fabric (Fig. 2).

One of the many uses to which my invention

is adapted is that of temporarily supporting the aerial of a portable radio. My novel wire-clips may be stuck into curtains or furniture at advantageous points about the room and the antenna may then be easily and quickly suspended 5 therefrom, removable at a moment's notice.

While I have illustrated and described a form of my invention, I do not wish to be limited thereby, as the scope of my invention is best 10 defined by the following claims.

I claim:

1. A wire-holding clip comprising a cap, pin means having a substantially circular portion, said cap having means to engage the substantially circular portion of said pin means, and said 15 cap having a wire-engaging member struck from the material of the cap, said wire-engaging member being bent outwardly and upwardly in spaced relation to the front face of the cap for the purpose described. 20

2. A wire-holding clip comprising a cap, a supporting pin having a head, said cap having a peripheral flange adapted to secure the head of said pin to said cap, said flange having prong means adjacent to said pin for the purpose of 25 engaging a fabric, and said cap having an integral wire-engaging hook for the purpose described.

3. A wire-holding clip comprising a cap part, 30 pin means associated with said cap part for supporting said cap part on a fabric, said cap part having a yieldable integral wire-engaging member struck from the material of the cap part, and said wire-engaging member being bent outwardly from and in spaced relation to the face of the 35 cap part for the purpose described.

4. A wire-holding clip comprising a cap part, fabric-engaging means associated with said cap part, an integral yieldable wire-engaging hook struck from the material of said cap part and extending a predetermined distance therefrom, said hook being bent upwardly in spaced relation to the face of said cap part to form wire-engaging surfaces to cooperate with the face of said cap part for the purpose described, and the free end 40 of said hook being spaced from said cap part a distance substantially less than the diameter of the wire to be engaged, thereby preventing the accidental disengagement of the wire and providing a spring action upon a wire being engaged 45 by said hook. 50

WALTER I. JONES.
